A. PAPINI.

RHEOSTAT:

APPLICATION FILED OCT. 13, 1919.

1,335,022.

Patented Mar. 30, 1920.

UNITED STATES PATENT OFFICE.

ANTONIO PAPINI, OF PHILADELPHIA, PENNSYLVANIA, ASSIGNOR TO A. MECKY COMPANY, OF PHILADELPHIA, PENNSYLVANIA, A CORPORATION OF PENNSYLVANIA.

RHEOSTAT.

1,335,022.

Specification of Letters Patent. Patented Mar. 30, 1920.

Application filed October 13, 1919. Serial No. 330,515.

To all whom it may concern:

Be it known that I, ANTONIO PAPINI, a subject of the King of Italy, having resided in the United States one year last past and having declared my intention of becoming a citizen thereof, residing in the city and county of Philadelphia, State of Pennsylvania, have invented a new and useful Rheostat, of which the following 10 is a specification.

My invention consists of a novel construction of a rheostat, comprising a suitable insulating casing, having a chamber therein filled with layers of mica mixed with graphite in suitable proportions and disks of metal or other conducting material arranged within said layers, said layers and disks being adapted to be compressed within said casing or cylinder, and provision being made 20 by means of a suitable pivoted spring arm contact device to vary the flow of the current, according to the position of the free end of said spring arm with respect to contact lugs on said disks, which latter project in alinement through a slot in the casing located below the free end of said spring arm contact.

It further consists of a novel construction of a slotted insulating casing or cylinder having a chamber therein for the reception of the resistance material and conducting disks, means being provided and carried on said casing for retaining said disks and resistance material in assembled 30 position and under suitable compression, which can be varied according to requirements.

It further consists of a novel construction of a contact disk made of metal or similar conducting material and provided with a projecting lug adapted to serve as a contact point.

It further consists of a novel construction of longitudinally slotted casing having a chamber therein for the reception of the resistance material and disks, said casing being provided with a plug or closure adapted to be actuated by a suitable threaded screw supported on a bar carried by said 40 casing.

It further consists of other novel features

of construction, all as will be hereinafter fully set forth and particularly pointed out in the claims.

For the purpose of illustrating my invention, I have shown in the accompanying drawings, forms thereof which are at present preferred by me, since they will give in practice satisfactory and reliable results. It is to be understood that the various instrumentalities of which my invention consists can be variously arranged and organized and that my invention is not limited to the precise arrangement and organization of these instrumentalities as here- 55 60 65 in shown and described.

Figure 1 represents a top view of a novel construction of rheostat, embodying my invention.

Fig. 2 represents a front view of Fig. 1. 70

Fig. 3 represents a section on line 3—3 of Fig. 2.

Fig. 4 represents a plan view of one of the disks and its contact lug in detached position. 75

Similar numerals of reference indicate corresponding parts.

Referring to the drawings:

1 designates my novel construction of rheostat, the same comprising the case or cylinder 2, which is preferably made out of porcelain or other refractory material, and having the holes 3 therethrough for the reception of the bolts 4, the heads 5 of said bolts being preferably seated in the recesses 6, so as to give a neat appearance to the casing and the latter being provided with the feet or legs 7, having the holes 8 therein for suitable fastening devices, whereby the casing can be fastened to the wall, floor 80 85 90 or other desired point.

The casing is provided with the cup-shaped cavity or chamber 9, within which are contained the layers 10 of resistance material, such as mica mixed with graphite in 95 suitable proportions, said layers being divided by the disks 11 of metal or the like, said disks each having a lug 12 thereon, which lugs serve as contacts and aline when the parts are assembled, as will be understood from Fig. 1. 100

13 designates a porcelain plug or closure,

which is engaged by the threaded headless screw 14, which passes through the bar 15, whose ends 16 have holes therein, through which pass the ends of the bolts 4.

5 The screw 14 has a slot 17 therein, so that it can be readily turned by a suitable implement, and the opposite end of said screw contacts with a seat 18 in the closure 13.

19 designates a spring arm contact, having the insulating finger piece 20 at one end and being fulcrumed or pivoted at 21.

22 designates a binding post having one end of the conductor 23 connected thereto, the other conductor 24 being connected to 15 the binding post 25, which comprises the binding post pin 26, which passes through the wall 27 of the casing 2 and is riveted to the contiguous end plate or disk 11 seen in Fig. 3, the parts being held in assembled position by the nut 28. 29 designates a conductor and 30 designates a longitudinally extending slot, in the top wall of the casing 2, through which the alining lugs or contacts 12 of the disks 11 project when the 25 parts are assembled, as seen in Fig. 1.

The operation is as follows:—

The parts having been assembled as seen in Figs. 1 and 2, it will be seen that the chamber 9 is filled with the layers of mica 30 and graphite 10 and the interposed disks 11. The plug or closure 13 having been placed in position and the desired amount of compression having been exerted thereupon by reason of the screw 14, it will be apparent that when the contact arm 19 is in the position seen in Fig. 1, which is its lowest position, the free end of said arm is positioned between a pair of contact lugs 12 and rests on the resistance material, so 40 that no contact is made with any of the disks 11, whereby no current passes, or in other words, the current is interrupted. Upon moving the arm 19 upwardly from the position seen in Fig. 1, it will be apparent that as said arm is moved with respect to the contact lugs 12 of the disks 11, the current will flow from the conductor 23 and will pass through the binding post 25, the pin 26, the disks upon which the free 50 end of the contact arm 19 contacts, and the resistance material between the disks, thence through the disk on which the contact arm 19 is set, then through the contact arm 19, the binding post 22 and conductor 23 to the apparatus or lamps back to the conductor 29.

As the lever or contact arm 19 is gradually moved to the top end of the rheostat seen in Fig. 1, the resistance is going to be 60 decreased accordingly, and when said contact 19 rests upon the uppermost or top disk 11, there will be a short circuit, or, in other words, the current will pass through all metallic conductors.

65 It will be apparent from the foregoing,

that my device can be readily and cheaply constructed, since the disks 11 with their lugs 12 are all of one uniform or standard size, and that the resistance material and disks having been assembled, the desired 70 amount of compression on the same can be readily attained by the rotation of the screw 14, and when it is desired to have access to the chamber 9 containing the resistance material and disks, this can be readily attained 75 upon the removal of the nuts from the bolts 4.

By arranging the contact lugs 12 in alignment within the slot 30, it will be apparent that the desired contact can be readily effected between the contact arm 19 and any desired contact lug 12.

It will now be apparent that I have devised a novel and useful rheostat, which embodies the features of advantage enumerated as desirable in the statement of the invention and the above description, and while I have in the present instance, shown and described a preferred embodiment thereof which will give in practice satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:—

1. In a rheostat, a casing of non-conducting material having a chamber therein, 100 layers of resistance material and disks contained within said chamber, said disks having contact points thereon projecting through a longitudinally extending slot in said casing, means for compressing said 105 disks and resistance material, and a spring contact arm rotatably mounted upon said casing and adapted to contact with said contact points.

2. In a rheostat, a casing of non-conducting material having a chamber therein open at one end and closed at the other, layers of resistance material and disks contained within said chamber, said disks having contact lugs projecting through a longitudinally extending slot in said casing, a closure for the open end of said chamber, means for actuating said closure, and a spring contact arm rotatably mounted upon said casing and adapted to contact with said lugs.

3. In a rheostat, a casing of non-conducting material having a chamber therein, open at one end and closed at the other, layers of resistance material and disks contained within said chamber, said disks having contact lugs projecting through a longitudinally extending slot in a wall of said casing, a closure for the open end of said chamber, bolts passing longitudinally through said casing, a bar extending across the open 130

end of said casing and retained in position by said bolts, and a screw carried by said bar and contacting with said closure for exerting pressure thereon.

5 4. In a rheostat, a casing of non-conducting material having a chamber therein, open at one end and closed at the other, layers of resistance material and disks contained within said chamber, said disks having contact lugs projecting through a longitudinally extending slot in a wall of said casing, a closure for the open end of said chamber, bolts passing longitudinally

through said casing, a bar extending across the open end of said casing and retained in position by said bolts, and a screw carried by said bar and contacting with said closure for exerting pressure thereon, in combination with a binding post pin passing through the closed wall of said casing and secured to the contiguous disk. 15 20

ANTONIO PAPINI.
